Attorney, Agent, or Firm—Birch, Stewart, Kolasch & Birch,
LLP[57] **CLAIM**

The ornamental design for a position sensing light device for a fishing rod, as shown.

DESCRIPTION

FIG. 1 is a perspective view of the position sensing light device for a fishing rod embodying our novel design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and,
FIG. 7 is a right side elevational view thereof.
